UNITED STATES PATENT OFFICE.

HERMAN RUMPF, OF BELLEVUE, AND FREDRICK RUMPF, OF NEWPORT, KENTUCKY;
SAID FREDRICK RUMPF ASSIGNOR TO SAID HERMAN RUMPF.

COLLAPSIBLE BOLSTER-ROLL.

1,071,799.

Specification of Letters Patent.

Patented Sept. 2, 1913.

Application filed November 16, 1910. Serial No. 592,695.

To all whom it may concern:

Be it known that we, HERMAN RUMPF and FREDRICK RUMPF, citizens of the United States, and residents, respectively, of Bellevue and of Newport, in the county of Campbell and State of Kentucky, have jointly invented certain new and useful Improvements in Collapsible Bolster-Rolls, of which the following is a specification.

10 It is the object of our invention to provide a collapsible bolster roll which is capable of being arranged in flat relation for purposes of shipment or storage and the like, and which is readily assembled into the 15 form of a roll, and the invention consists in the novel construction of the parts, and in the novel arrangements and combinations of the parts hereinafter more fully described and claimed.

20 In the drawings: Figure 1 is a perspective view of our improved device in set-up relation. Fig. 2 is a longitudinal section of the same on a line corresponding to the line 2-2 of Fig. 4. Fig. 3 is a longitudinal section of the same on a line corresponding to the line 3-3 of Fig. 4. Fig. 4 is a cross-section of the same on a line corresponding to the line 4-4 of Fig. 2. Fig. 5 is a perspective view of one end of our improved 30 device in partly closed relation. Fig. 6 is a perspective view of our improved device in collapsed relation. Fig. 7 is a perspective view of the pivot-pin for securing the anchor-strips in place.

35 The bolster-roll comprises the longitudinal strips 11, 12, between which a preferably resilient sheet 13 is secured. This resilient sheet is preferably of card-board or of stiffened fiber.

40 14, 14, are end transverse strips and 15, 15, are intermediate transverse strips of spring material, for instance spring steel, which are secured respectively to the said flexible sheet, as by eyelets 16, 17.

45 18 is a covering of suitable material which is preferably received over the resilient sheet 13 and bent inwardly under the longitudinal strips, the under-turned edges of said covering being secured to the inner 50 faces of said longitudinal strips by tacks 19. The resilient sheet is secured to said longitudinal strips, as by tacks 20, the intermediate transverse strips being let into grooves 21 in said longitudinal strips under

said flexible sheet, forming a flexible body 55 or frame-work for the bolster-roll.

24, 24 are anchor-strips having connection with the respective end transverse strips 14 and are normally arranged along the inner face of said transverse strips as shown in 60 Fig. 6. These anchor-strips are of spring-material, as spring steel, and are brought into action when it is desired to mount the roll in set-up form. These anchor-strips are arranged to be swung upon pivot-pins 26 65 from the position shown in Fig. 6 to the position shown in Fig. 5, and then into the set-up relation shown in Fig. 4, and are arranged for being received in end-slots 28 in the ends of the respective longitudinal 70 strips, the construction being such that the spring stress of said anchor-strips will be exerted upon the end transverse strips intermediate of the ends thereof, as at the pivot-pin connections, and at the ends of said 75 end transverse strips and intermediate of the ends of said anchor-strips, as at the walls of the end-slots 28, for bracing said end transverse strips and anchor-strips upon each other and arranging the end 80 transverse strips and the anchor-strips in a united bowed or circular form as shown in Fig. 4.

When the anchor-strip is brought into set-up relation, the face thereof which is adjacent to the end transverse strip when in collapsed relation, is brought to a position facing away from said end transverse strip, by the swinging of said anchor-strip on its pivot, as clearly shown by a comparison of 90 Figs. 6, 5 and 4.

The pivot-pins are preferably received through slots 29 in said anchor-strips, the pins preferably being provided with elongated heads 30 which are arranged to be 95 received in said slots when the anchor-strips are in abnormal position, as shown in Fig. 5. The slots are provided further to permit movement of the anchor-strip lengthwise across the shanks of the pins, and prevent binding between the parts, when the framework is being bent into set-up relation.

Tie-bands 31, 32 are secured to the bolster-roll adjacent to the ends of the intermediate 105 transverse strips 15 and are arranged to be tied as shown at 33 for forcing the edges of said bolster-roll to proper relative distance

when in set-up relation and giving the same its proper transverse curvature while maintaining proper longitudinal parallelism of the outer surface of the roll.

34 are aprons with which the ends of the roll-body are provided and 35 are aprons with which the anchor-strips are provided, 36 being gathering cords for gathering the adjacent inner edges of said aprons at the respective ends of said roll when the roll is in set-up relation for forming the end rosettes 37. The provision of the aprons 35 upon the anchor-strips is for the purpose of closing the gap at the ends of the bolster-roll which would otherwise be left in said ends by the provision of the space 38 between the longitudinal strips when the bolster-roll is in set-up relation. In this manner a complete rosette for each end of the bolster-roll is provided, made up of a plurality of the aprons having a common gathering cord, the auxiliary aprons 35 being positioned intermediate of the ends of the main aprons 34 when the bolster-roll is in set-up relation. The space 38 which forms the gap between the longitudinal edges of the roll when in set-up relation permits pillows to be placed within the bolster-roll.

Having thus fully described our invention, what we claim as new and desire to secure by Letters Patent is:

1. In a collapsible bolster-roll, the combination of a body comprising longitudinal edge-strips, a spring anchor-strip, releasably securing means between said spring anchor-strip and said body, and main and auxiliary aprons respectively secured to the ends of said body and to said anchor-strip, for forming an end rosette for said roll when in set-up relation.

2. In a collapsible bolster-roll, the combination of a resilient body, spring anchor-strips pivoted at both their ends to said body, said spring anchor-strips having one of their sides presented toward said body when in collapsed relation and arranged to be swung sidewardly in arcs about their pivots for forming both said body and spring anchor-strips in oppositely bowed form with the other sides of said respective spring anchor-strips presented toward said body when in set-up relation, and bracing means opening in the direction of length of said bolster-roll for fixing said body and spring anchor-strips in oppositely bowed set-up relation, substantially as described.

3. In a collapsible bolster-roll, the combination of a resilient body, spring anchor-strips pivoted at both their ends to said body, said spring anchor-strips having one of their sides presented toward said body when in collapsed relation and arranged to be swung sidewardly in arcs about their pivots for forming both said body and spring anchor-strips in oppositely bowed form with the other sides of said respective spring anchor-strips presented toward said body when in set-up relation, and bracing means opening in the direction of length of said bolster-roll for fixing said body and spring anchor-strips in oppositely bowed set-up relation, substantially as described.

3. In a collapsible bolster-roll, the combination of a resilient body, spring anchor-strips pivoted at both their ends to said body, said spring anchor-strips having one of their sides presented toward said body when in collapsed relation and arranged to be swung sidewardly in arcs about their pivots for forming both said body and spring anchor-strips in oppositely bowed form with the other sides of said respective spring anchor-strips presented toward said body when in set-up relation, and main aprons secured to the ends of said body and auxiliary aprons secured to said spring anchor-strips, for forming end rosettes for said roll when in set-up relation, substantially as described.

In testimony whereof, we have signed our names hereto in the presence of two subscribing witnesses.

HERMAN RUMPF.
FREDRICK RUMPF.
